UNITED STATES PATENT OFFICE.

DANIEL McCAUGHAN AND ARCHIE McCAUGHAN, OF MAMMOTH, UTAH TERRITORY.

CAR-COUPING.

SPECIFICATION forming part of Letters Patent No. 531,738, dated January 1, 1895.

Application filed February 19, 1894. Serial No. 500,790. (No model.)

To all whom it may concern:

Be it known that we, DANIEL McCAUGHAN and ARCHIE McCAUGHAN, citizens of the United States, residing at Mammoth, in the 5 county of Juab, Utah Territory, have invented certain new and useful Improvements in an Automatic Car-Coupler; and we do declare the following to be a full, clear, and exact description of the invention, such as will 10 enable others skilled in the art to which it appertains to make and use the same, reference being had to the accompanying drawings, in which—

Figure 1 is a longitudinal vertical section 15 of the coupler. Fig. 2 is a front elevation. Fig. 3 is a horizontal section. Fig. 4 is a top plan view. Fig. 5 illustrates the automatic coupling device. Figs. 6 and 7 show one of the coupling jaws. Figs. 8 and 9 show one 20 of the jaw cranks, and Figs. 10, 11 and 12 illustrate the coupling lever in detail.

The object of our invention is to provide an 25 automatic car coupler which is simple and effective, and which will uncouple automatically in case the cars leave the track.

The coupler consists of a pair of hinged jaws in a draw-head, with which a headed link engages. A fixed tongue opens the jaws automatically in case the drawhead swings to 30 one side beyond a certain limit of safety.

The outer end of the draw bar A has a solid 35 head with upper and lower flanges a forming semicircular recesses to receive similarly shaped ears b on the rear end of the link chamber B. A vertical bolt C passes through registering holes in the ears and draw-head and hinges them together. On each side of these ears are shoulders which will strike the shoulders a' of the draw-bar and prevent the 40 link chamber from swinging laterally beyond a certain angle. The draw-bar has a fixed tongue a^2 projecting forward into the link chamber. The front of the link chamber is open, and in each of its side walls is a recess b' whose front ends are preferably rounded, 45 as shown best in Fig. 3. In the top of the link chamber and in line with these recesses, are holes of suitable size to permit the coupling jaws D to be dropped through them into 50 the link chamber. At the upper end of each

jaw plate d is a journal d' , and at the lower end a journal d^2 , the latter fitting into a suitable hole in the bottom of the link chamber. A block B' is fitted snugly into the hole in the top through which the jaw plate passes, 55 leaving only room for the upper journal d' to turn easily. The rounded end of the recess b' fits the edge of the jaw plate. Surmounting each journal d' and rising above the top of the link chamber is a square head d^3 which 60 receives a jaw crank E, consisting of a flat plate having teeth e at one end and a square hole e' at the other end to fit the head d^3 . On each side of the link chamber and adjacent to the journals of the jaw plates is an upright ear b^2 . A transverse shaft F' is journaled in said ears, and serves as the fulcrum for the coupling lever F, which is preferably 65 a bent lever having teeth f on one arm to engage with the teeth e on both jaw cranks E. 70 On the other arm of the lever is a weight f' , and in the end of the lever is an eye f^2 for the attachment of a cord or chain connecting it with the unlocking devices at the side or top of the car. The weight keeps the lever 75 normally in the position shown in Fig. 1, and by reason of the intermeshing teeth f , e , the jaw plates are held out at an angle as shown in Figs. 3 and 4.

The link G is a bar having at each end a 80 head, provided with beveled shoulders g and a tapered end g' .

The operation of our invention is as follows: The link enters the link chamber and pushes the coupling jaws sidewise back into 85 the recesses b' until the head of the link passes through them, when they are automatically swung together again, by the falling of the weighted lever F, which the separation of the jaws has raised. The ends of 90 the jaw plates close against the shoulders of the link and the coupling is effected. To uncouple, it is simply necessary to lift the lever F, which operates to swing the jaw plates back into their recesses b' leaving the link 95 free to be withdrawn. In case the car leaves the track, the link chamber will be swung so far to one side, that one of the jaws will come against the fixed tongue a^2 , and the jaw plates will be crowded apart and release the 100

link as shown in Fig. 5, thus automatically uncoupling the cars.

Having thus described our invention, what we claim is—

- 5 1. The combination with a draw bar, having a tongue, of a link chamber horizontally hinged on said drawbar, and coupling jaws mounted in said chamber on each side of said tongue, substantially as described.
- 10 2. The combination with a drawbar, of a link chamber horizontally hinged thereto, coupling jaws vertically hinged in said link chamber, a crank on each jaw, and an elbow lever fulcrumed on a horizontal axis and positively interengaged with the adjacent ends of both cranks, substantially as described.
- 15 3. The combination with the chamber A, of the link chamber B horizontally hinged thereto, the jaws D having journals received in holes in the top and bottom of the link chamber, the cranks E having teeth e, and the

weighted lever F having teeth f engaging the teeth e, substantially as described.

4. In a car coupling, a link chamber having holes in its top to admit coupling jaws, and blocks partially filling said holes to retain said jaws in place, substantially as described.

5. A car coupling provided with hinged jaws to engage with a headed link, and means for automatically opening said jaws when the car leaves the track, substantially as described.

6. A car coupling comprising a laterally movable draw-head, hinged coupling jaws mounted in said draw-head, and means for automatically opening said jaws when the draw-head swings beyond the limit of safety, substantially as described.

DANIEL McCAUGHAN.

ARCHIE McCAUGHAN.
